(57) **CLAIM**

The ornamental design for operating device for ultrasonic control device, as shown and described.

DESCRIPTION

FIG. 1 is a top, front and right side perspective view of an operating device for ultrasonic control device showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a perspective view thereof showing the design in environment use; and,

FIG. 8 is another perspective view thereof showing the design in environmental use.

The broken lines shown represent unclaimed subject matter and form no part of the claimed design.

The solid shaded areas in FIGS. 1, 2, 4 and 6-8 are to show a contrast in appearance.
